(57) **CLAIM**

The ornamental design for a pail for use, for example, as a waste container, as shown and described.

DESCRIPTION

FIG. 1 is a perspective view of a pail for use as, for example, a waste container showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a perspective view of a second embodiment of a pail for use as, for example, a waste container showing my new design;

FIG. 9 is a front view thereof;

FIG. 10 is a rear view thereof;

FIG. 11 is a top view thereof;

FIG. 12 is a bottom view thereof;

FIG. 13 is a left side view thereof; and,

FIG. 14 is a right side view thereof.

The scoop shown in broken lines in some figures is included for the purpose of illustrating environment and forms no part of the claimed design.

The broken lines showing of a knob, a pedal and an opening in the figures are included to show portions of the pail for use as, for example, a waste container and form no part of the claimed design.
